UNITED STATES PATENT OFFICE.

DUDLEY WOOD AND A. BYINGTON, OF BYRON, ILLINOIS.

IMPROVEMENT IN PLOWS.

Specification forming part of Letters Patent No. **28,323**, dated May 15, 1860.

To all whom it may concern:

Be it known that we, DUDLEY WOOD and ALBERT BYINGTON, of the town of Byron, in the county of Ogle and State of Illinois, have invented a new and Improved Mode of Constructing Plows; and we do hereby declare that the following is a clear, full, and exact description of the construction and operation of the same, reference being had to the annexed drawings and the letters of reference marked thereon, making a part of this specification, in which—

Figure 1 is a perspective view, and Fig. 2 a longitudinal section.

The nature of our invention consists in the arrangement of devices hereinafter described.

The advantages of our invention consist in, first, obtaining very great strength and firmness with a small amount of metal by means of tubular form of both beam and standard and the deep seat in the line of draft upon the top of the standard, on which the beam rests and is bolted; second, the facility with which lodged stalks, stubble, or other material is disposed of by being forced up within the front curvature of beam and standard, from which place they fall out of the way with the furrow-slice—a result which, though arrived at by a flat beam and standard cast in one piece, we believe is new in a plow of separate beam and standard; third, the ease with which our plow, after being built, can be disconnected by removing the inside bolts, *a a*, and bolt *b*, for the purpose of grinding and polishing the mold-board preparatory to being finished for use. This cannot be done where the beam and stand-

ard are cast in one piece, as in various other plows.

The operation or manner of connecting and disconnecting the beam and standard is to place the two bolts *a a*, which are square, close to the heads, with the heads downward into the recesses cast within the standard. They are thus held in their places while the beam with corresponding holes through its center is dropped down over them to its seat upon the top. The end of the iron brace from the handle is slipped over the rear bolt, and the nuts are then put on and screwed down tightly. The bolt of the secondary joint *b* is afterward inserted and made fast with a nut. This makes a perfect attachment of both beam and standard, and also secures both handles firmly to the beam.

A reversal of the above-described process of course disconnects the whole.

The handles, share, clevis, &c., are of the usual construction, and our plow is used in tilling in the ordinary manner.

We do not claim the tubular beam separately; but

What we claim, and desire to secure by Letters Patent, is—

The arrangement of the tubular beam *A*, tubular standard *B*, secondary joints *b*, and inside coupling-bolts, *a a*, substantially as described.

DUDLEY WOOD.
ALBERT BYINGTON.
